CLAIM

The ornamental design for a crown, as shown and described.

DESCRIPTION

FIG. 1 is a perspective view of a crown showing our new design;

FIG. 2 is a front view thereof;

FIG. 3 is a left side view thereof, a right side view being omitted since it is a mirror image of the left side view;

FIG. 4 is a bottom view thereof;

FIG. 5 is a top view thereof;

FIG. 6 is a rear view thereof; and,

FIG. 7 is an enlarged view of a portion of the crown shown within the area designated as 7 in FIG. 1.

The surface shading lines on the jewels indicate the transparent material.

The broken lines depict the portions of the crown that form no part of the claimed design. The broken lines in FIGS. 1 and 7 indicating an enlargement portion of the design form no part of the claimed design.
